UNITED STATES PATENT OFFICE.

JEAN A. YOUNG, OF MILLVILLE, NEW JERSEY.

COBBLER'S JACK.

Application filed March 26, 1926. Serial No. 97,742.

The invention relates to an appliance for use in the mending of shoes and provides an article adapted equally well for a right hand or a left hand workman, and which may be 5 adjusted to a variety of positions to facilitate the repair and lessen the effort required to complete the work.

While the drawings illustrate a preferred embodiment of the invention it is to be understood that in adapting the means to meet specific needs and requirements, the design may be varied and such other changes in the minor details of construction may be resorted to within the scope of the invention 15 as claimed, without departing from the spirit thereof.

For a full understanding of the invention and the merits thereof, reference is to be had to the following description and the drawings hereto attached, in which—

Figure 1 is an elevational view of a jack for the use of cobblers, embodying the invention, the dotted lines showing an adjusted position of the upper portion of the 25 device,

Figure 2 is a side view of the jack,

Figure 3 is an enlarged detail sectional view on the line 3—3 of Figure 2,

Fig. 4 is a horizontal sectional view on the 30 line 4—4 of Figure 1, the dotted lines illustrating the upper portion of the jack swung outwardly.

Corresponding and like parts are referred to in the following description and designated in the several views of the drawings 35 by like reference characters.

The jack comprises a post or standard 1, which is preferably hollow and consisting of a 40 length of pipe of suitable diameter. A floor plate 2, threaded to the lower end of the post 1, is secured to the floor by lag screws or other suitable fastening means. Clips 3 connect the upper end of the post 1 to a stand 4, or other suitable support. Complemental 45 brackets 5 and 6 are mounted upon the post 1 and are pivotally connected by means of a bolt 7. The brackets 5 and 6 are of similar formation, each consisting of an upper arm and a lower arm, the several arms terminating in line with the post 1 in the normal 50 position of the brackets. The pivoted ends of the brackets 5 and 6 are approximately of circular outline and overlap, as shown most clearly in Figure 4 and are pierced to receive 55 the pivot bolt 7. The outer or free ends of both arms of the bracket 5 and the lower

arm of the bracket 6 are apertured, as indicated most clearly in Figure 3, and the outer or free end of the upper arm of the bracket 6 is formed with a depending portion 8 which enters the upper end of the post 1 and provides a journal for the bracket to turn about. The lower arm of the bracket 6 receives the post 1 which passes through the opening in the outer or free end thereof. 65 In the normal position of the brackets they are disposed in the same plane, the one above the other, and with the upper bracket 5 resting upon the lower bracket 6. A packing 9, such as a disc of leather is secured to the 70 top side of the bracket 6 and operates as a noise deadener between the two brackets. A clip 10 is attached to the stand 4 or analogous support and is adapted to receive the 75 bolt 7 when it is required to hold the brackets 5 and 6 against outward movement. When the bolt 7 is disengaged from the clip 10, the brackets 5 and 6 may be swung laterally about the post 1, as indicated by the dotted lines in Figure 4

The numeral 11 designates a last, which may be of any construction and which, as shown, comprises a head and a shank. A carrier is provided for the last and consists of an elongated head 12 and a shank 13, the latter passing through the openings in the outer ends of the arms comprising the upper bracket 5. The shank 13 is hollow and its lower end projects below the lower arm of the bracket 5 and receives a stop collar 90 14 which prevents vertical displacement of the shank. A washer 15 of leather, or analogous material is slipped upon the shank 13 and is disposed between the head 12 and the upper arm of the bracket 5 and supplements the action of the packing 9 in deadening noise and cushioning the blow of a hammer upon the last. The last 11 is detachably fitted to the head 12, thereby admitting of a selected last being placed in position to meet the size of the shoe being repaired or the particular nature of work in hand. A strap 16 is provided to hold the work upon the last. A slide 17 freely movable in the shank 13 has the lower end of the strap 16 connected thereto and a hand-piece 18 projecting outwardly from the slide 17 is adapted to operate in a vertical slot 19 formed in a side of the shank 13. Notches 20 formed in the walls of the slot 19 are adapted to receive the hand-piece 18 and prevent upward movement thereof when

pressed downwardly to cause the strap 16 to hold the work upon the last.

As indicated by the dotted lines in Figure 1, the upper bracket 5 may be turned upon the bolt 7, thereby bringing the work in convenient position. When the bolt 7 is released from the clip 10, both brackets 5 and 6 may be swung laterally, as indicated by the dotted lines in Figure 4, thereby admitting of adapting the jack for a right hand, or a left hand workman.

Having thus described the invention, I claim:

1. In a cobbler's jack, a post, a lower bracket comprising spaced arms, one of the arms extending over the post and having a depending portion entering the post and the other arm being apertured to receive the post which passes therethrough, an upper bracket pivoted to the lower bracket and including spaced arms, a last carrier having a hollow shank mounted in the arms of the upper bracket, and a work holder including a member within the said shank and a strap extending through the shank and the top of the last carrier.

2. In a cobbler's jack, a support comprising upper and lower arms, a last carrier including an elongated head having openings in opposite end portions and having a hollow shank in line with one of the open-

ings pivotally mounted in the arms of the said support and slotted in a side between the said arms, a last removably fitted in the other opening of the last carrier head, a strap for holding the work on the last extending into the hollow shank of the last carrier through the opening of the head thereof in line with said shank, a slide within the shank having the said strap attached thereto, and a hand piece projecting laterally from the slide and operating in the slot formed in the side of the said hollow shank.

3. A cobbler's jack comprising a post, a lower bracket having two arms, one of the arms embracing the post and the other arm having a depending journal entering the upper end of the post, an upper bracket pivoted to the lower bracket to move therewith and having an independent pivotal movement in the plane thereof, a last carrier mounted in the upper bracket and having a longitudinally slotted hollow shank mounted in the walls of the slot, a work holder, a slide within the hollow shank and connected to said work holder, and a hand piece projecting from the slide through the slot of the hollow shank and adapted to co-operate with the notched walls thereof.

In testimony whereof I affix my signature.

JEAN A. YOUNG. [L.S.]
